FIRE ESCAPE

Joseph P. Chodacki and John Kaminski,
Detroit, Mich.

Application May 26, 1947, Serial No. 750,588

2 Claims. (Cl. 254—151)

1

The purpose of our invention is to provide a device by means of which a person, in an emergency, may lower himself or herself safely from an elevated location in a structure such as a building, when normal avenues of descent, such as stairways or elevators have been cut off by reason of fire or possibly some other cause.

Our purpose is to provide a device of simple construction inexpensive in cost and compact in bulk so that it may be placed incontrusively in a room, such as a hotel room, in close proximity to an outside window.

Another, and more specific purpose of our improvement is to provide a device of this kind in which the rate of speed at which a person may lower himself or herself to the ground, will not be appreciably affected by the variable factor of weight of the respective person. In other words, the purpose of our improvement is to provide a device including means to prevent undue acceleration of the descent of a person, irrespective of his or her weight.

We shall now describe our device with reference to the accompanying drawings, in which,

Fig. 1 is a perspective view of our device including its outer casing, which is broken off in part for better illustration of the elements therein;

Fig. 2 is a longitudinal sectional view of our device;

Fig. 3 is a sectional view on line 3—3 of Fig. 2;

Fig. 4 is also a sectional view on line 3—3 but shows pertinent elements of the device in different operative positions;

Fig. 5 is a sectional view on line 5—5 of Fig. 2.

Similar numerals refer to similar parts throughout the several views.

The device, in the main, comprises a casing 10, a reel 11, mounted within the casing, a cable 12 wound upon the reel and means to retard the unreeling of the cable, which means are the main novel feature of our invention.

The casing may be made in any suitable form. As shown in Fig. 1 it is substantially rectangular and is provided with a cover 13. The end walls 14 are provided with internal bosses 15 for location of bearings for axle 16 of the reel. The reel includes a hollow midsection 17, serving as a spool for cable 12, and end flanges 18. It will be understood that the reel is keyed to the axle and that it rotates therewith. Integrally formed with the flanges on the outside, in axial relation thereto, are hubs 19 which carry a plurality of spoke-like retarders 20. These are made of flat strips of resilient material such as steel or rubber, and are inserted at one end into radial slots

2

21 in said hubs, the flat surfaces of the strips being disposed at right angle to the plane of the flanges. The flexibility of the strips must be such that normally said strips maintain their radial positions, but on encountering an obstacle, as will be presently described, will bend out of the way of said obstacle on application of sufficient driving force. At this point we wish to state that strips made of rubber have proved entirely satisfactory, although we do not wish to be limited to rubber as a material for the manufacture of said retarders.

It will be understood that the strips ought to be held within the hubs by suitable means. This may be done either by having them cemented in their respective slots, or by forming the strips with expanded shank portions to fit into slots correspondingly expanded at their bottom portion so as to prevent the withdrawal of said strips radially.

To secure the strips against lateral displacement a circular plate 22 is affixed over the outer surface of each hub, in axial relation thereto, by means of screws 23.

Disposed within the casing 10, around the reel, in a spaced relation thereto, and parallel to axle 16, are four tubular members 24. These members extend from one end of the casing to the other, and being supported by the end walls thereof, are close enough to the reel to be in the path of strips 20.

The cable mentioned above, is wound up upon reel 11, the outer end of said cable passing outwardly of the casing through an aperture 25, and is equipped with a suitable belt 26 or a suitable harness which the person about to utilize the device, is to secure upon his or her body.

As the total weight of the device is small as compared with the weight of an average person, the device as a whole, must be attached to some fixed heavy object, such as a radiator, or to some structural part of the respective room, such as a door or a wall. To facilitate this, the casing carries a metal eye 27 for application of a chain or a cable 28, which is shown in fragment. A crank 30 fitting over an angular end 29 of axle 16 serves as a means of reeling up the cable once it has been unwound.

We shall now describe the operation of our device. It will be assumed that cable 12 is all wound up on reel 11, that casing 10 is attached to a suitable stationary object, and that a person having secured upon himself or herself belt 26, has stepped off or jumped off into space from the elevation where the device is located. Im-

mediately, under the weight of the person, and under the pull of that weight upon the cable, the reel will be set into a rotary motion.

With the rotation of the reel, strips 20, carried by hubs 19, will encounter tubular members, or impact bars 24. As the encounter is at first limited to the mid-portion of each strip and as the strips are flexible the upper portion of each strip extending radially beyond the bar will, by the momentum of the motion, bend over said bar in an enwrapping motion as shown in Fig. 3. As the rotation of the reel is continued, the strips will be flexed rearwardly as shown in Fig. 4, but will continue bearing frictionally in a wiping motion against the bars until the rotary progression of the reel will have carried the respective strips out of engagement therewith. Immediately the strips will straighten out only to encounter the respectively next impact bars where the above described flexing of the strips will be repeated.

Under ordinary circumstances, without the use of my retarding means, the reel would tend to rotate faster with increase of weight upon the cable. The use of my strips, prevents this eventuality, for the higher the initial speed of the reel before the first encounter of the strips with the impact bars, the higher would be the force of the momentum in wrapping the upper portions of the strips over said impact bars, so that, within certain limits, the action of the strips provides automatic means of keeping the speed of the reel within bounds of safe unreeling.

It will be understood that the strips above described do not have to meet the impact bars at the same time, but that they may be arranged so as to effect first the encounter of a part of the number of strips with the impact bars, then the encounter of other strips. Obviously the number of the strips and the bars may be varied, and the number of strips may exceed the number of impact bars, or vice versa.

After having described our device, and the use thereof, what we wish to claim is as follows:

1. In a fire escape including a cable wound up

on a reel and having a free end adapted for application of a load, means to retard the rotation of the reel under said load, the means including a hub axially extending from one end of the reel and structurally connected thereto, a plurality of flexible strips extending radially from the hub, a plurality of impact bars disposed around the reel in parallel relation thereto and to each other, and extending transversely in the path of the strips 5 said strips extending normally well beyond the respective bars, the outer end portions of the respective strips being adapted to wrap themselves around the bars upon an impact therewith during the rotation of the reel, but being adapted to be pulled out of engagement with said bars on continuation of the rotation of the reel.

2. As a means of retarding the rotation of a reel under a pull of a cable wound thereon, in combination, a hub of the reel extending endwise 20 therefrom, a plurality of flexible strips radially mounted within the hub member and extending beyond the outer limit of the reel, and a plurality of impact bars disposed around the reel parallel to its axis and in the path of the strips during the 25 rotation of the reel, the strips being flexible enough to have their outer ends wrap themselves over the bar in the direction of rotation of the reel, on impact with the bars, and being capable of being flexed back out of engagement with the 30 bars on continuation of rotation of the reel.

JOSEPH P. CHODACKI.
JOHN KAMINSKI.
